UNITED STATES PATENT OFFICE.

ALLYN R. REESE, OF DENVER, COLORADO.

BASKET-BALL-GOAL INDICATOR.

Application filed June 21, 1922. Serial No. 569,896.

To all whom it may concern:

Be it known that I, ALLYN R. REESE, a citizen of the United States, residing at Denver, in the county of Denver and State of Colorado, have invented certain new and useful Improvements in Basket-Ball-Goal Indicators, of which the following is a specification.

This invention relates to basket ball goals and its primary object is to provide in association with a basket of the type used in the game of basket ball, an indicator appliance which either visually or audibly gives notice of the fact that the ball has passed through the basket and a goal is made.

My improvements relate particularly to apparatus of the character shown and described in the reissue application No. 538-119 of United States Patent No. 1,381,466, filed on the twentieth day of February, 1922, and it is a further object of the present invention to provide in an indicator appliance for basket ball goals, a mechanism which transmits the movement of a lever extending in the path of the ball through the basket, to an operating member of the indicating element; still other objects of the invention reside in the formation of a basket which guides the ball to a central point thereof, in the provision of simple means for rendering the indicating appliance inoperative in case its service is not required, in providing a device to prevent the operation of the indicator should the ball after actuating the lever in the basket, fail to pass through the opening at the lower end thereof, and in details of construction and a novel and practical arrangement of parts, all of which will fully appear in the course of the following description made with reference to the accompanying drawings.

In the drawings in the several views of which corresponding parts are similarly designated—

Figure 1 represents a side elevation of the improved basket ball goal;

Figure 2, a horizontal section taken on the line 2—2, Figure 1;

Figure 3, a rear view of the frame on which the indicating appliance is mounted, looking in the direction of the arrow A, Figure 1;

Figure 4, an enlarged fragmentary elevation of the upper parts of the appliance, showing the hammer element which in the

operation sounds the gong, in its raised position;

Figure 5, an enlarged plan view of the hammer element looking in the direction of the arrow B, Figure 3;

Figure 6, a vertical section through the frame, the indicating mechanism mounted thereon, and the lower support of the basket, taken on the line 6—6, Figure 3, the parts of the mechanism having been shown in their normal condition of rest;

Figure 7, an enlarged view of the upper portions of the parts of the mechanism as shown in Figure 5;

Figure 8, a fragmentary section in the same plane as that of Figure 5 but drawn to a larger scale, showing the parts of the mechanism in the position they occupy after the ball has struck the lever extending in the basket;

Figure 9, an elevation of the goal showing the operation of the device which restrains actuation of the indicating appliance in case the ball fails to pass through the lower end of the basket;

Figure 10, an enlarged section taken on the line 10—10, Figure 2;

Figure 11, a detail view of a modification of the spring catch of the operating mechanism; and

Figure 12, a fragmentary section showing a plan view of the weighted portion of the operating lever.

Referring more specifically to the drawings, the reference character 2 designates a metal bracket by which the lower part of the basket and the indicating appliance are mounted on a wall or other upright support.

The bracket comprises a body member 3 having rearwardly extending arms 4 provided with apertures in their angularly bent extremities for the passage of the nails, screws or bolts by which the structure is fastened to its support.

The frame has at its lower portion, forwardly projecting apertured lugs 5 to which is bolted in a horizontal position, the lower one of two annular members 6 and 7 which conjointly form the rigid frame of the basket.

The upper member 7 of the basket frame is fastened to the support above and independent of the bracket structure 2, and it is braced by rods 8 which are fastened to the support at lower points.

The lower member 6 of the basket frame, is angular in cross section to provide an abutment for an annular member of the operating lever of the indicating appliance, 6 which will hereinafter be more fully described, and it is braced by rods 9 which connect its sides at diametrically opposite points with the bolts or other fastening devices by means of which the upper arms 10 of the bracket are attached to the support.

The basket proper is composed of a number of leather straps 10 which are fastened to the two ring-shaped members of the frame at substantially equal distances from 15 each other, and which are interconnected by circular bands 12 and 13.

The lower one of these circular bands, disposed above the lower member of the rigid frame, is made of relatively small diameter so that the upright straps are drawn inwardly at the point at which it is connected therewith to form a comparatively narrow throat through which the ball must pass.

25 The principal object of this construction of the basket is to prevent the ball from coming in contact with the metal parts thereof, which might cause it to rebound and fall outside the basket without passing 30 through the lower end thereof, and which possibly might injure the soft leather with which the ball is covered.

The indicatory appliance hereinbefore referred to, consists of a gong 14 which is fastened on the bracket by means of a central bolt 15. A lever 16 fulcrumed on the bracket, as at 17, has a ring-shaped arm 18 which normally rests in the angular recess of the lower annular member of the basket 40 frame, as best shown in Figure 6 of the drawings, and whose opposite arm is enlarged to provide a counterpoise 19 which serves to maintain the parts in their normal position of rest.

45 A plurality of interconnected leather straps 20 detachably fastened to the ring 18 by buttons 21 or other suitable means, and stretched across the same, provides a slightly resilient net with which the ball 50 engages as it passes through the basket. It will be evident that the lever thus constructed serves as a trap-door which is held yieldingly in its normal position by its counterweight and is moved downwardly 55 by the impact of the ball when it is tossed into the upper end of the basket.

The lever thus moved from its obstructive position, allows the ball to pass through the lower end of the basket and by its return 60 movement under the influence of its counter weight, causes the gong to be sounded through the instrumentality of a mechanism, the construction of which will now be described.

A hammer 22 adapted to strike the gong

by a downward movement, is pivoted on the bracket, as at 23, co-axially with a carrier-arm 24 which in the operation of the mechanism, functions to lift the arm to an elevated position and causes it to sound the 70 gong when subsequently released.

The carrier-arm is normally held in contact with a seat 25 on the bracket by a spring 26 which is coiled around the collar 75 by which the arm is mounted on the pivot pin upon which both the arm and the hammer are supported.

A spiral spring 27 connects the free ends of the arm and hammer, and a stop 28 on the arm limits the upward movement of the 80 hammer by the contraction of this spring.

A lug 29 on the carrier arm is in the operation of the mechanism engaged by the upper end of a lifter bar 30 which moves in a guide loop 31 on the bracket, in pivotal 85 connection with the weighted arm of the operating lever.

90 The upper end of the lifter bar is bifurcated and straddles a plate 32 which forms the upper transverse part of the bracket. The finger 33 of the bifurcation, at the inner side of the plate, is that which engages the lug on the hammer-carrier, as stated hereinbefore, and the other finger 34 extending at the outside of the plate, has at its 95 extremity an inturned point 35 which in practice rides across the plate.

A beveled protuberance 36 formed on the plate in the path of the point on the lifter bar, serves to impart a lateral movement to 100 the bar 30 during certain periods of its reciprocating motion, as will hereinafter be explained, and a U-shaped spring-catch 37 fastened at the front of the cross-plate and curving around the lower edge thereof, engages with the inner finger of the lifter bar 105 so as to yieldingly maintain the outer finger of the same, in contact with the plate.

110 The upper end of the free arm of the spring curves outwardly over the corresponding end of the finger and into the path of the lug 29 on the hammer-carrier, which is beveled at its upper side to permit of its passing the spring during its upward movement.

115 In order to prevent excessive deflection of the free part of the spring and to hold the same against lateral displacement, the spring catch may be constructed as shown in Figure 11. The free part of the spring of the catch extending at the inner side of the cross-plate of the bracket is, in the modification, shortened and a strip 38 of more rigid metal is fastened at the end thereof and curved outwardly at its extremity, as 120 in the first described form.

125 The screw-bolt 39 by which the fixed end of the spring is fastened to the plate, is made of sufficient length to extend through an aperture in the other part of the same 130

and thereby restrain said part from lateral displacement.

In the operation of the invention, a ball tossed into the open upper end of the basket, engages with the net-covered arm of the lever and by its impact causes the same to move downwardly about its fulcrum against the resistance of the counterweight which normally holds the lever in the position in which it obstructs the passage through the basket, by engagement with the lower annular member of the basket frame.

The narrow throat of the basket, formed by the band 13, guides the ball to the center of the net work on the lever and prevents it from coming in contact with the rigid metal part 6 of the frame.

During the downward movement of the lever by the impact of the ball, the lifter bar is raised from the normal position, illustrated in Figures 6 and 7, in which the in-turned point 35 at the end of its outer finger engages with the protuberance 36 on the cross-plate 32 and its other finger engages with the free part of the U-shaped spring catch and holds it under tension.

The bar 30, by its upward movement, engages with the lug 29 on the carrier-arm 24 and raises the same about its pivotal axis together with the hammer with which it is connected through the medium of the spring 27.

The finger 34 of the lifter bar is during its upward movement disengaged from the protuberance 36 on the cross-plate with the result that the spring 37 is released to expand to the position shown in Figure 8 in which its out-curved extremity is in the path of the lug on the hammer-carrier.

When, after having been released by the ball passing through the basket, the lever returns to its original position under the influence of its counter weight, the spring catch retains the hammer element in its raised position until the outer finger of the lifter bar re-engages the protuberance and thereby retracts the catch from the lug on the carrier.

The withdrawal of the spring leaves the carrier and the hammer free to move downwardly under the influence of the force of gravity and the torsion of the spring 26 and the impetus of the element thus impelled, is such that after the carrier arm has been brought to a stop by engagement with the seat 25 it normally engages, the hammer will continue its downward movement and strike the gong after which it is immediately retracted by the contraction of the spring 27 which connects it with the carrier.

The clear sounding of the gong as a result of the momentary impact of the hammer, announces to the players of the game that a goal has been made.

Inasmuch as the gong is not sounded until

after the ball has passed through the basket, all chance of dispute is obviated by the use of my invention and if, as for example during a practice game, the service of the indicatory appliance is not required, it is 70 readily rendered inoperative by removal of the net work which spans the ring of the lever.

In order to prevent sounding of the gong in case the ball after having actuated the 75 lever, fails to pass through the lower end of the basket either by a rebound or by an obstruction to its downward movement, I have provided a device which under such a condition will retain the lever in its lowered position and restrain it from active motion until after it has been engaged by the next ball tossed into the basket.

This device, which is best shown in Figure 9 of the drawings, consists of a rod 40 80 which is pivotally supported between lugs 41 at the front of the annular member of the basket structure and which is held in engagement with the underside of the net-covered arm of the lever by a torsional 85 spring 42 shown in Figure 2.

The rod has at its free end, a fork 43 and if by a rebound or other cause, the ball fails to move the lever to the full extent of its downward motion, this fork will upon the 90 return movement of the lever engage with its ring as shown in full lines in Figure 9, and thus prevent it from returning to its normal position and thereby sounding the gong.

If, while the lever is thus being held in an 100 inoperative position, the ball is again tossed into the basket, its impact with the lowered arm of the lever will cause it to complete its downward stroke. The ball while passing through the basket throws the rod outwardly as indicated in broken lines in Figure 9, so that after the parts are released, the lever will have reassumed its normal 105 position before the rod is moved into engagement with the underside thereof by the 110 torsion of its spring.

Having thus described my improved goal in the best and most practical form at present known to me, I desire it understood that many variations in the construction and arrangement of its parts may be resorted to within the spirit and scope of the invention as defined in the hereunto appended claims.

A visual indicatory instrument may for example, be employed auxiliary to or in the 115 place of the gong which audibly announces the passage of the ball through the basket, or an electrical appliance may be substituted for the mechanism actuated by the movement of the lever, to sound the gong 120 or operate any other indicating device that may be used, by the closing of a circuit.

What I claim and desire to secure by Letters Patent is:

1. In a basket-ball goal, the combination

- with a basket, of a lever in the path of a ball passing through the basket, an indicatory device, mechanism for the operation of said device, and means for the actuation of 5 said mechanism by movement of the lever.
2. In a basket-ball goal, the combination with a basket, of a lever in the path of a ball passing through the basket, an indicatory device, mechanism adapted to operate 10 said device after the lever has been moved by the passage of a ball through the basket, and means for the actuation of the mechanism by movement of the lever.
3. In a basket ball goal, the combination 15 with a basket, of a counterweighted lever adapted to be moved by a ball passing through the basket, a gong, a hammer co-operating therewith, and mechanism for the actuation of the hammer by movement of 20 the lever.
4. In a basket ball goal, the combination with a basket, of a counterweighted lever adapted to be moved by a ball passing through the basket, a gong, a hammer co- 25 operating therewith, and mechanism for the actuation of the hammer by the return movement of the lever.
5. In a basket ball goal, the combination with a basket, of a counterweighted lever 30 adapted to be moved by a ball passing through the basket, a gong, a pivoted hammer-element adapted to sound the gong, a lifter adapted to raise said element by downward motion of the lever, a catch adapted 35 to move automatically into the path of the hammer element to obstruct its return movement, and means co-operating with the lifter to retract the catch at a determinate point in the return movement of the lifter and thereby 40 release the hammer element.
6. In a basket ball goal, the combination with a basket, of a counterweighted lever adapted to be moved by a ball passing through the basket, a gong, a pivoted ham- 45 mer, a pivoted carrier adapted to engage the same in its upward movement, a resilient connection between the hammer and the carrier, a rest limiting the downward movement of the carrier, a lifter adapted to raise
- the carrier by downward motion of the lever, a catch to obstruct the return movement of the carrier, and means co-operating with the lifter to retract the catch at a determinate point in the return movement of the lifter and thereby release the hammer 55 element.
7. In a basket ball goal, the combination with a basket, of a counterweighted lever adapted to be moved by a ball passing through the basket, an alarm element, a lifter pivotally connected with the lever, and having a pair of fingers at its upper end, a hammer element adapted to be raised by the engagement of one of said fingers during upward movement of the lifter, a 60 spring-catch adapted to move automatically into the path of the hammer element to obstruct its downward movement, and means co-operating with the other finger during downward movement of the lifter, to retract the catch by lateral motion of the lifter and thereby release the hammer element. 65
8. In a basket ball goal, the combination with a basket having a passage for the ball, 70 of a lever, a flexible net on an arm of the lever, which in the normal position of the same obstructs the passage of the basket, an indicatory device, and means for the operation of said device by movement of the lever 75 when the net thereon is engaged by a ball thrown into the basket.
9. In a basket ball goal, the combination with a basket, of a lever extending across the opening thereof to be moved downwardly by a ball passing through the basket, an indicatory device, means for the operation of said device by a determinate movement of the lever, and a restraining device actuated by the ball in its movement 80 through the basket, and adapted to interlock with the lever at a determinate point in its downward movement whereby to restrain its upward motion. 85
- In testimony whereof I have affixed my 90 signature.

ALLYN R. REESE.
